BODY RELAXING LOUNGE CHAIR

Oscar T. Buffalow, Chattanooga, Tenn.

Application March 31, 1958, Serial No. 725,276

9 Claims. (Cl. 128—57)

This invention relates to body relaxing apparatus and more particularly to a lounge chair having a relaxing attachment that reciprocates in an opening in the back of the chair.

One object of this invention is to provide a lounge chair having a relaxing attachment reciprocated by an endless chain or fabric belt traveling in a circuitous path.

Another object is to provide a relaxing chair having a resilient roller extending through an opening in the back of the chair in contact with a flexible covering over the opening, the roller being reciprocated by a carriage moved along a track by an endless chain or fabric belt.

A further object of this invention is to provide a relaxing chair having a resilient roller extending through an opening in the back of the chair in contact with a flexible covering over the opening, the roller being reciprocated by a carriage moved along a track by an endless chain or fabric belt actuated through speed reduction means by a motor.

Still another object is to provide a body relaxing chair having a resilient roller extending through an opening in the back of the chair in contact with a flexible covering over the opening, the roller being so mounted as to adjust itself automatically to the contour of the patient's body.

Other objects and advantages of the invention will be apparent from the following description, taken in conjunction with the accompanying drawings, in which:

Fig. 1 is a side elevation, partly broken away, showing a lounge chair with an adjustable back to which one embodiment of this invention is applied;

Fig. 2 is an enlarged sectional elevation, on the line 2—2 of Fig. 4 illustrating clearly the construction of the relaxing attachment shown in place on a chair in Fig. 1;

Fig. 3 is a further enlarged sectional view of a part of the apparatus shown in Fig. 2, showing details of construction of the roller, carriage and casters.

Fig. 4 is a sectional view, along the line 4—4 of Fig. 2, of the roller, carriage, casters and rails;

Fig. 5 is a partial sectional view, similar to Fig. 4, of the carriage with casters and rails of a modified construction; and

Fig. 6 is a fragmentary view of a modification of the speed reduction drive means shown in Figs. 1 and 2, including a motor driving an endless chain through a worm and gear connection.

Referring now to the drawings, there is shown a lounge chair 1, preferably of the overstuffed type of construction, having a back 2, which is adjustable to many positions between the vertical position shown in full lines and the horizontal position shown in broken lines in Fig. 1. An opening 3 is formed in the central portion of the back extending substantially from the top to the bottom of the back, or in a longitudinal direction. A flexible covering 4 is firmly attached to the front surface of the back, thereby covering the opening 3. The flexible covering may consist of one or more layers of fabric, plastic, leather, rubber, or any other suitable material having adequate characteristics of flexibility, strength and comfort.

2

A relaxing roller 5 is supported for free rotation by a carriage 6 which is mounted by means of four casters 7, journaled thereon, for travel along a track comprising a pair of rails 8 suitably supported on and attached to a framework secured to the back 2.

The carriage 6 comprises a truck 9 to which a bell crank member 10 is pivotally attached, as at 11. The member 10 includes two like parallel plates 12, between the one ends of which an axle 13 is fixed, as by means of bolts 14 having countersunk flat heads, the bolts passing through openings in the plates 12 into tapped holes in the ends of the axle 13. The relaxing roller 5 may comprise a wooden core 15, freely rotatable upon the axle 13, and an outer portion 16 of rubber or other suitable resilient material.

To the other ends of the plates 12 are attached the one ends of two tension springs 17, the other ends of which are attached to the truck 9. The construction is such that, as the carriage 6 rolls on its casters 7 along the rails 20 8, the tension springs 17 cause the bell crank member 10 to rotate forwardly on its pivot 11, thereby forcing the resilient roller 5 to bulge the covering 4 outwardly somewhat, as illustrated in Figs. 1 and 2. When a patient is seated in the chair 1 with his back resting against the covering 4 on the back 2 of the chair, the resilient roller 5 will be forced gently, but firmly, against the covering 4 by the springs 17 and the roller will automatically adapt itself to the contour of the patient's back as it is rolled upwardly and downwardly in the opening 3.

As illustrated in Fig. 4, the casters 7 may be V-grooved in construction and the bearing surfaces of the rails 8 may be V-shaped to conform closely to the shape of the casters. The casters are thus held in place on the track and the carriage is prevented from abutting against the sides of the framework, not shown. Also, the rails 8 have extensions 8A thereon forming channels with close tolerances with respect to the peripheries of the casters 7 which are opposite from the rails 8, thus preventing movement of the casters and thereby of the carriage 6 away from the rails.

As illustrated in Fig. 5, a modification of this construction may comprise casters 18 which are single-flanged and rails 19, the bearing surfaces of which are rectangular in shape, the rails guiding the casters and thereby the carriage to prevent side-to-side movement of the carriage. The rails 19 have extensions 19A forming channels for confining the casters 18, to prevent movement of the casters and the carriage away from the rails.

A connecting rod 20 is pivotally attached at one end by 60 means of a ball or oilite bearing 21 to the carriage 6. The other end of the connecting rod is attached by means of a ball bearing 22 to a link of an endless chain or fabric belt 23, mounted for movement in a circuitous path around a pair of sprockets 24 and 25, suitably supported 55 for free rotation in a framework attached to the back 2, at points spaced from each other and adjacent the ends of the opening 3.

As illustrated in Figs. 1 and 2, the chain 23 may be moved, through a train of pulleys of different diameters 60 and belts connected between them, by an electric motor 26. Thus, the motor 26 rotates a small drive V-pulley 27 around which passes a V-belt 28, also passing around a large V-pulley 29, which is journaled on the framework attached to the back 2. The axle 30 to which the V-pulley 65 29 is fixed is driven thereby and, in turn, drives a small V-pulley 31, a V-belt 32 and a large V-pulley 33, which is attached to an axle 34 and, through it, drives the sprocket 25 and thereby the chain 23. As the chain 23 travels along its circuitous path around the sprockets 24 and 25, through the connecting rod 20, it draws the carriage 6 and thereby the freely rotating roller 5, the roller

moving upwardly and downwardly in the opening 3, rolling against the flexible covering 4.

In place of the train of pulleys illustrated in Figs. 1 and 2, a modification of the speed reduction means may comprise a worm and gear connection, as illustrated in Fig. 6. The motor 26 drives, through its drive shaft 35 and a coupling 36, a worm 37, in driving engagement with a gear wheel 38 which, in turn, drives a small sprocket 39, with which the chain 23 is meshed for driving engagement.

A possible modification of this invention is that the chain 23 may be replaced by a fabric V-belt or a fabric cog belt, to which the connecting rod is pivotally attached in a manner similar to the pivotal attachment 22 of the connecting rod to the chain.

Another modification is that there may be two or more of the rollers 5, rather than only one, mounted on the carriage 6.

By varying the length of the special relaxing mechanism made in accordance with this invention, it is adaptable to use in a suitable couch or table for use in the home or office.

By this invention, there is provided a means of relaxing the back of a patient which is comfortable, removes congestion, and also promotes better circulation in general, especially to the thirty two pairs of spinal nerves which help to regulate and control the circulation. So long as the motor is operating, the freely rotating resilient roller travels continuously up and down, relaxing the spine of the patient through the flexible covering 4. Due to the action of the tension springs 17 acting on the bell crank member 10, the resilient roller 5 automatically adapts itself to the contour of the patient's back as it rolls upwardly and downwardly. Through one of the speed reduction means provided, the speed of rotation of the motor is reduced to a speed of travel of the resilient roller which is most comfortable and effective in treating the back of the patient.

It will be apparent to those skilled in the art that various changes may be made in the invention, without departing from the spirit and scope thereof, and therefore the invention is not limited by that which is shown in the drawings and described in the specification, but only as indicated in the appended claims.

I claim:

1. A relaxing lounge chair comprising a chair having a back, said back having an opening extending centrally thereof in a longitudinal direction, a flexible covering over said opening, a track comprising two rails attached to said back and extending parallel to said opening, a carriage supported on casters rolling on said rails, a freely rotating

resilient roller supported by said carriage in contact with said flexible covering through said opening, a pair of sprockets rotatably supported by said back adjacent the ends of said opening, an endless chain mounted for movement around said sprockets, a connecting rod pivoted to and connecting said carriage with said chain, a motor for driving said chain and speed reduction means connected between said motor and one of said sprockets.

2. The invention according to claim 1 in which the bearing surfaces of the rails are V-shaped and the wheels are V-grooved.

3. The invention according to claim 1 in which the bearing surfaces of the rails are rectangular and the casters are single-flanged.

15 4. The invention according to claim 1 in which the speed reduction means comprises a train of pulleys of different diameters and belts connected between them.

5. The invention according to claim 1 in which the speed reduction means comprises a worm and gear connection.

20 6. The invention according to claim 1 in which the roller is resiliently urged against the flexible covering.

7. The invention according to claim 1 in which there are a plurality of freely rotating resilient rollers supported 25 by the carriage.

8. The invention according to claim 1 in which the endless chain is replaced by an endless fabric belt.

9. A relaxing lounge chair comprising a chair having a back adjustable between vertical and horizontal positions, said back having an opening extending centrally thereof substantially from top to bottom of said back, a flexible covering over said opening, a pair of rails attached to said back and extending parallel to said opening behind said covering, a carriage mounting casters rolling on said rails, a freely resilient roller supported by said carriage and spring-pressed into contact with said covering through said opening, a pair of sprockets rotatably supported by said back at spaced points adjacent the ends of said opening, an endless chain mounted for movement 30 around said sprockets, a connecting rod pivoted to and connecting said carriage with said chain, a motor for driving said chain and speed reduction means connected between said motor and one of said sprockets.
